FAUCET AND VALVE SEAT DRESSING STONE

Joseph E. Bartlett, 215 S. Parker Ave.,
Olathe, Kans. 66601

Filed Mar. 8, 1974, Ser. No. 449,252

Term of patent 14 years

Int. Cl. D8—05

U.S. Cl. D8—90

FIG. 1 is a perspective view of a faucet and valve seat dressing stone showing my new design;

FIG. 2 is a side elevational view of the dressing stone;

FIG. 3 is a view partly in section of the dressing stone taken along line 3—3 of FIG. 2 in the direction of the arrows;

FIG. 4 is a top plan view of the dressing stone taken along line 4—4 of FIG. 2 in the direction of the arrows; and

FIG. 5 is a bottom plan view of the dressing stone taken along line 5—5 of FIG. 2 in the direction of the arrows.

I claim:

The ornamental design for a faucet and valve seat dressing stone, as shown and described.
